HEADER DISK MOUNTING

Frederick E. Stag, Brooklyn, N. Y., assignor to
International Cigar Machinery Company, a corporation of New Jersey

Application May 21, 1948, Serial No. 28,347

5 Claims. (Cl. 131—93)

1

This invention relates to cigar machines, more particularly to improvements in the mounting of the header disk thereof.

One of the main objects of this invention is to provide horizontal and/or vertical adjustment of the header disk to position the same in various positions required by different shapes of the head ends of the cigars being operated on, or by different operating conditions.

Heretofore the header disk was supported by an arm mounted on a stud carried by a lever operated to move the header disk into operative position to apply the flag end of a wrapper to the head end of a cigar bunch. This stud extends transversely of said cigar wherefore said arm may be adjusted thereon with the header disk to accommodate different shapes of cigar heads, but the header disk cannot be adjusted to engage the flag end of the wrapper higher or lower on the head of the cigar as required for different operating conditions.

With the particular embodiments of my invention illustrated herein the header disk may be adjusted to engage the flag end of the wrapper higher or lower on the head of the cigar as required for different operating conditions.

In the accompanying drawings which form a part of this specification:

Fig. 1 is a side elevation of a header disk mounting embodying my invention, the relative position of the header block being shown in dot-and-dash lines;

Fig. 2 is a similar view of a modified form of my header disk mounting;

Fig. 3 is an end elevation of the header disk mounting shown in Fig. 1; and

Fig. 4 is a partial plan view of the header block portion of a cigar wrapping mechanism provided with the header disk mounting shown in Figs. 1 and 3.

While the invention is susceptible of various modifications and alternative constructions, it is here shown in the drawings and will hereinafter be described in a preferred embodiment. However, it is not intended that the invention is to be limited thereby to the specific construction disclosed, but it is intended to cover all modifications and alternative constructions falling within the spirit and scope of the invention as defined in the appended claims.

Referring now to Figs. 1 and 4 of the drawings, it will be observed that there is shown therein a header block 10 which is supported on a frame 15 which is fragmentarily shown in Fig. 4. The construction of the header block 10

2

and frame 15 is fully disclosed in the Durning Patents 2,369,777 and 2,290,171.

A cigar C (Fig. 4) is produced by spirally winding a wrapper about a cigar bunch while the latter is supported and revolved by an upper pair of rollers 35, 36 and a lower pair of rollers 37, 38. During this operation the head end of the cigar bunch is supported in the header block 10. These rollers correspond to similarly numbered rollers of the aforesaid Durning Patent 2,290,171. Each of the top rollers 35 and 36 may be similarly supported by brackets 40 corresponding to brackets 40 of said patent and by brackets (not shown) corresponding to the brackets 39 of said patent and connected to brackets 40 by tie rods 41. The brackets supporting the upper rollers 35 and 36 are pivoted on the ends of the rollers 37 and 38 and supported in a manner fully described in said Durning Patent 2,290,171. Suitable mechanism for opening and closing the rollers to admit therebetween the cigar bunch to be wrapped and to permit the cigar C so produced to be removed is shown in said Patent 2,290,171. Suitable gearing for driving the rollers and thereby revolving the cigar bunch while the wrapper is being spirally wound thereon is fully described in the Halstead Patent 1,915,277.

The tuck end of the wrapper is initially applied to the tuck end of the cigar bunch by a tuck needle (not shown) fully disclosed in said Patent 2,290,171 while the cigar bunch is being revolved by the rollers. The continued rotation of the rollers winds the wrapper spirally about the cigar bunch and the flag end of the wrapper (not shown) is slit by mechanism fully described in Durning Patent 2,369,777.

At this time the header disk cone 141 is rapidly moved by its mounting, which will be presently described, into a position wherein it engages the flag end of the wrapper and applies it to the head end of cigar C while the same is supported and revolved in the header block 10. In this manner the flag end of the wrapper will be properly applied to the head end of cigar bunch. For this purpose the header cone 141 is revolvably mounted in a conventional manner on a shank 141a clamped in the split end of arm 142 by a screw 142a. Arm 142 is mounted on a lever 144 by a device which will be presently described. Lever 144 is provided with a split hub which is clamped by a screw 145 on a shaft 146 supported in a boss 147 of frame 15.

The device for connecting arm 142 to lever 144 includes a stud 143 clamped in the split end of lever 144 by a screw 160. A head 162, which may

be secured on or formed integrally with stud 143, has an inner arcuate face in which is formed a groove 164. The arm 142 has an arcuate face which fits the inner arcuate face of head 162 and is provided with a tongue 166 which fits the groove 164. A screw 168 extending through a slot 170 formed in head 162 is threaded into arm 142 to retain the same when it is adjusted vertically relative to head 162, as indicated by the arrows in Fig. 1, to the various positions indicated in dotted lines in Fig. 1. Thus the header cone 141 will engage the flag end of the wrapper higher or lower on the head end of the cigar during the application thereof to the cigar bunch and cause the flag end to be applied smoothly according to the contour of the head end.

Moreover, upon unloosening the screw 160, the header cone 141 may be turned with arm 142 and head 162 about an axis extending transversely of cigar C to fit different shapes of head ends of cigars which are to be operated on. It will be understood that different shapes of head ends will require replacement of header block 10 by a header block fitting the particular shape of head end. Thus the header cone 141 may be adjusted relative to lever 144 in either direction indicated by the arrows in Fig. 3 to various positions, at either side of its initial position, which are indicated by dotted lines in Fig. 3. Since the curvature of the inner radial face of head 162 is concentric with the tip of header cone 141, and the axis of stud 143 passes through the same, these adjustments of the header cone will not displace its tip from the position required during the operation thereof on the head end of the cigar C.

The shaft 146 may be turned by suitable mechanism such as shown in the Durning Patent 2,369,777, or the Halstead Patent 1,915,277, to engage the header cone 141 with the head end of cigar C during the application of the wrapper thereto, and then return the header cone to its operative position.

Referring now to Fig. 2 wherein a preferred form of my header disk mounting is illustrated. The header disk 241 is revolvably mounted on a shank secured to one end of its supporting arm 242 in the same manner as header disk 141. The split portion of arm 242 at its other end is clamped on a stud 243 by a screw 260. A lever 244 has a split hub, which is clamped by a screw 245 on the shaft 146 after the arm 144 has been removed therefrom. A socket formed in the upper end of lever 244 has an unthreaded portion 268 in which is located a ball head 266 which is formed on the stud 243. Seat 262 formed in lever 244 completes the socket to retain ball head 266. This socket also has a threaded portion 268 into which is threaded a plug 270. Plug 270 engages the ball head 266 of stud 243 and thereby retains the arm 242 and header disk 241 in position to permit the latter to engage the head end of the cigar on header block 10 and thereby apply the flag end of the wrapper thereto in the same manner as described in connection with Figs. 1 and 4.

Upon unloosening plug 270 the arm 242 may be turned either about an axis transverse to the cigar or an axis parallel thereto, or both, to various positions of the header disk required for proper application of the flag end of the wrapper. With this construction also the header disk may be adjusted to engage the flag end of the wrapper higher or lower on the head end of the cigar to apply the flag end, as required for different conditions of operation.

The seat 262 is sufficient to retain the ball head

266 but allows movement of the shank of stud 243. Thus vertical adjustment of the header disk 241 by rotation at 266 in the directions indicated by the arrows in Fig. 2, as well as rotational adjustment of the header disk around the longitudinal axis of stud 243. This latter adjustment varies the angle of the disk without disturbing the locus of its apex.

What is claimed is:

1. In a cigar machine header mechanism having a header block adapted to support the head end of a cigar to which the flag end of a wrapper is to be applied and a shaft adapted to be turned to and fro, the combination with a lever mounted on said shaft, of an arm, a device connecting said arm to said lever, and a header disk mounted on one end of said arm and arranged to engage the head end of a cigar on said header block and apply the flag end of a wrapper thereto, said device including a connecting member having one end thereof secured in the other end of said arm, a ball-shaped portion on the other end of said connecting member, said lever having a socket enclosing and closely fitting said ball-shaped portion whereby the second-mentioned end of said arm may be adjusted universally relative to said lever to accommodate different shapes of cigar heads on said header or cause said header disk to engage a higher or lower portion of the head end of said cigar, as required for different operating conditions, and means for retaining said arm in any particular position to which it may be adjusted relative to said lever.

2. In a cigar machine header mechanism having a header block adapted to support the head end of a cigar to which the flag end of a wrapper is to be applied and a shaft adapted to be turned to and fro, the combination with a lever mounted on said shaft, of an arm, a device connecting said arm to said lever, and a conical header disk mounted on said arm and arranged to engage the head end of a cigar on said header block and apply the flag end of a wrapper thereto, said device including a head, said head being pivotally mounted on said lever for adjustment about an axis extending transversely of said cigar and intersecting the tip of said header disk and having an upwardly extending arcuate face concentric with the tip of said header disk, said arm having an arcuate face fitting the arcuate face on said head, and means for securing said arm to said head with their arcuate faces fitting each other whereby said arm may be adjusted upwardly or downwardly relative to said head without displacing the tip of said header disk to cause the header disk to engage the flag end of a wrapper higher or lower on the head end of the cigar to which the wrapper is being applied.

3. A header disk mounting comprising a supporting member adapted to be secured on a shaft, an arm, a device connecting said arm to said member, and a conical header disk mounted on one end of said arm and adapted to engage the head end of a cigar and apply the flag end of a wrapper thereto, said device including a connecting member having one end thereof secured in the other end of said arm, a ball-shaped portion on the other end of said connecting member, said supporting member having a socket enclosing and closely fitting said ball-shaped portion whereby said second-mentioned end of said arm may be adjusted horizontally or vertically relative to said supporting member, and means for retaining said arm in any

particular position to which it may be adjusted relative to said supporting member.

4. A header disk mounting comprising a supporting member adapted to be secured on a shaft, an arm, a device connecting said arm to said member, and a conical header disk mounted on said arm and adapted to engage the head end of a cigar and apply the flag end of a wrapper thereto, said device including a head, said head being pivotally mounted on said member for adjustment about an axis extending transversely of said cigar and intersecting the tip of said header disk and having an upwardly extending arcuate face concentric with the tip of said header disk, said arm being provided with an arcuate face fitting the arcuate face on said head, and means for securing said arm to said head with their arcuate faces fitting each other whereby said arm may be adjusted horizontally relative to said member and upwardly relative to said head without displacing the tip of said header disk.

5. In a cigar machine a header mechanism having a header block adapted to support the head end of a cigar to which the flag end of a wrapper is to be applied, a shaft adapted to be turned to and fro, a lever secured to said shaft, a support rotatably mounted within said lever, means for holding said support in various adjusted po-

sitions relative to said lever, an arm rotatably mounted relative to said support, said arm having a header disk of cone shape mounted on one end thereof in closely adjacent operative relation to the header block to engage the head end of a cigar on said block and apply the flag end of a wrapper thereto, said arm having an approximate center at the apex of the cone of the header disk about which rotation of the other end of the arm relative to the support may be effected in an arc with the said apex as the approximate center thereof.
